US0D1047167S

(12) United States Design Patent (10) Patent No.: US D1,047,167 S
(45) Date of Patent: * Oct. 15, 2024

(54) MASSAGER

(71) Applicant: AROMATICACO., Seoul (KR)

(72) Inventor: Seok Jin Lee, Seoul (KR)

(73) Assignee: AROMATICACO., Seoul (KR)

() Term: 15 Years

(21) Appl. No.: 29/859,975

(22) Filed: Nov. 15, 2022

(30) Foreign Application Priority Data

May 18, 2022 (KR) 30-2022-0019732

(51) LOC (14) Cl. 24-01

(52) U.S. Cl.

USPC D24/215; D24/200
